[57] CLAIM

The ornamental design for an aircraft warning light, substantially as shown and described.

DESCRIPTION

FIG. 1 is a side elevation view of an aircraft warning light in accordance with our novel design, the opposite side being a mirror image;

FIG. 2 is a top view thereof;

FIG. 3 is a bottom view thereof;

FIG. 4 is an elevational view thereof taken from the left end of the light as shown in FIG. 1; and

FIG. 5 is an elevational view thereof taken from the right end of the light as shown in FIG. 1.
